UNITED STATES PATENT OFFICE.

ARVID WESTERBERG, OF DJURSHOLM, SWEDEN.

ELECTRIC FURNACE.

1,412,764.

Specification of Letters Patent. Patented Apr. 11, 1922.

Application filed November 17, 1915. Serial No. 61,937.

To all whom it may concern:

Be it known that I, ARVID WESTERBERG, a citizen of the Kingdom of Sweden and resident of Djursholm, Stockholm län, Sweden, have invented certain new and useful Improvements on Electric Furnaces, of which the following is a specification.

My invention relates to electric furnaces, which are being operated by means of electric currents from a power source which does not permit heavy fluctuations in the load. In such case some kind of resistance is as a rule employed in series with the furnace in order to lessen the variations in the power supplies.

Said resistances should preferably be adjustable and inductive rather than of the non-inductive kind in order to economize with the supply of energy.

Such resistances or choking coils, which consist of a certain number of turns of copper around iron core, offer, as usually made, certain disadvantages. When only some of the turns of the winding are carrying an alternating current, an electromotive force is generated also in the other turns, which complicates in a certain way the switching mechanism necessary for adjusting the choking powder of the coil.

The present invention has for its object to obviate the before-mentioned difficulty by arranging the choking coils as illustrated in the diagrammatic view of the drawing, which accompanies the specification.

Choking coils indicated by 1 are arranged on an iron core 2 provided with three legs *a*, *b*, and *c*. The middle one of these, *b*, is left without winding, one of the outside legs *a* is wound with twice as many turns as the other outside leg *c*. It is, however, clear that the proportion of the number of turns on *a* and *c* may be changed as desired.

The magnetic field excited by the winding on one of the outside legs may pass through the path offered therefor by the central leg of the iron core; for this reason the other outside winding may be short-circuited without inconvenience.

Adjustment in three steps may be obtained by short-circuiting one or the other or both of the outside windings, which may be done by means of only two circuit breakers 3 and 4. One of said circuit breakers may be equipped with an overload release arrangement.

If an overload occurs in the furnace this circuit breaker automatically introduces a corresponding reactance in the circuit, limiting the overload without breaking the current in the furnace.

60

If more than 3 regulating steps are necessary more than 2 legs may be provided with choking coils. Each one of said coils may be short-circuited independently of the other coils by providing one or more legs without windings, which act as one or more magnetic shunts as described above. The drawing illustrates a transformer having a primary winding 5 and a secondary winding 6 delivering current to a pair of electrodes 7. The invention is not limited to any certain method of arranging the electrodes of an electric furnace, but may be usefully employed in connection with any kind of electric furnaces. Of course, the same results, 75 which are obtained by the choking coil described above, may be obtained by using two or several ordinary choking coils of known construction, but this method will be more expensive and will take up more space. 80

Having now clearly described my invention I hereby claim and desire to secure by Letters Patents of the United States of America:

1. In an electric furnace the combination 85 of a plurality of choking coils in series with the furnace all the coils being arranged on one iron core provided with a magnetic shunt without windings.

2. In an electric furnace the combination 90 of a plurality of choking coils in series with the furnace, all the coils being arranged on one iron core provided with a magnetic shunt without windings, the number of turns in each coil being different from the number of 95 turns of the other coils.

3. In an electric furnace the combination 100 of a plurality of choking coils in series with the furnace all the coils being arranged on one iron core provided with a magnetic shunt without windings and with a circuit breaker in parallel with the coil adapted for short-circuiting the coil.

Signed at Stockholm, Stockholm län, Sweden, this 3d day of November, A. D. 105 1915.

ARVID WESTERBERG.
